UNITED STATES PATENT OFFICE.

JAMES S. WILSON, OF SCRANTON, PENNSYLVANIA.

GRATE STRUCTURE.

Application filed October 17, 1922. Serial No. 595,103.

To all whom it may concern:

Be it known that I, JAMES S. WILSON, a citizen of the United States, residing at Scranton, in the county of Lackawanna and 5 State of Pennsylvania, have invented certain new and useful Improvements in Grate Structures, of which the following is a specification.

This invention relates to improvements in 10 furnace grate structures and more particularly to an improved grate frame.

In the ordinary construction of grate frames it is customary to secure the frame members together at the corners of the 15 frame by means of bolts or similar fastening devices. However, as the bolts are of metal of one type and the frame members are of metal of another type, the parts will expand and contract unequally with the result that they will become distorted or fractured. Furthermore, when the frame is being installed or when repairs become necessary, great inconvenience is experienced in applying the securing means for the corners 20 of the frame, or in removing them, in the latter instance. Therefore, it is one of the primary objects of the present invention to provide a grate frame in which the frame members will be so constructed as to adapt 25 them to be fitted together at their ends and securely held connected without the employment of any extraneous fastening means such as bolts and the like, so that in installing the frame within the furnace fire 30 box, no difficulty will be experienced in connecting together the ends of the frame members, and likewise, in making repairs, any of the frame members may be readily 35 removed and without the annoyance usually 40 experienced.

Another object of the invention is to provide the frame members with means whereby their ends may be connected with one another in a manner to insure of rigidity of 45 the structure and a more firm union of the parts in consonance with the weight imposed thereon.

Another object of the invention is to provide the frame members with means forming 50 an integral part thereof for connecting their ends at the corners of the frame so that because of the integral nature of these connections, they will expand and contract to an equal degree with the bodies of 55 the members thereby effectually providing against distortion, warping, or fracture of

the frame members under the conditions noted.

In the accompanying drawings:

Figure 1 is a perspective view of the grate 60 structure embodying the invention;

Figure 2 is a perspective view of the mating ends of two of the frame members;

Figure 3 is a detail horizontal sectional 65 view through one corner of the frame structure.

In the drawings the frame of the grate structure is indicated in general by the numeral 1 and the same comprises side members 2 and 3 and end members 4. 70

As previously stated it has heretofore been the custom to secure together the sides and ends of the frame at the corners of the frame by means of bolts or other fastening devices constituting parts separate from the frame members themselves. The present invention, however, contemplates providing the ends of the frame members with interlocking parts integral therewith and adapted to interfit in a manner to firmly and securely connect the corners of the frame. Each end member 4 of the frame is provided at each end with a boss 5 formed by casting the said end member with a recess 6 of which one face 7 of the boss constitutes a 85 wall, the bottom wall of the recess being indicated by the numeral 8, and another bounding wall by the numeral 9. The boss 5 is provided upon its face opposite its face 7 with a rib 10, one face 11 of which is disposed at an obtuse angle to the plane of the face upon which the rib is formed and which face is indicated by the numeral 12. The edge face of the rib 10 is indicated by the numeral 13 and is disposed at an obtuse 90 angle to the plane of the face 11. The face 7 of the boss 5 is inclined in the direction of the upper end of the boss, and this end of the boss terminates short of the plane of the upper side of the frame member 4. Likewise the said face 7 of the boss is obliquely disposed with relation to the plane 95 of the face 12 of said boss. The boss 5 may therefore be said to be tapered in the direction of its upper end as well as in the direction of its inner side where it joins the face 9 of the end member 4 and therefore has, generally speaking, the form of a double wedge.

Each side member 3 of the frame structure is cast at each end with a recess 14 forming a depending boss 15 designed to 100 105 110

seat within the recess 6 when the end of the said member 3 is seated over the boss 5. The face of the boss 15 which defines one wall of the recess 14, and which face is indicated by the numeral 16, is diagonally disposed so as to coact with the face 7 of the boss 5, and likewise this face 16 is inclined in the direction of the top of the recess 14 so that the recess is gradually decreased in width in the direction of its said top or upper end. The opposite wall of the recess 14 has surface portions 17, 18 and 19, the portion 17 occupying a plane at right angles to the plane of the face of the said side member 3 and being therefore designed to seat beside the face 12 of the boss 5. The face portion 18 is diagonally disposed with relation to the recess 14 and is designed to seat beside the face 11 of the boss 5, the portion 19 of the said wall of the recess 14 being disposed at an obtuse angle to the portion 18 so as to seat beside the edge face 13 of the said boss 5. It will now be evident that when the frame members are to be connected at their ends the ends of the side members 3 are fitted down over the ends of the end members 4 so that the bosses 5 will seat within the recesses 14 and the bosses 15 will seat within the recesses 6. Thus the parts will be interfitted in such a manner that the bosses 5 will wedge into the recesses 14 due to the disposition of the faces of the said bosses 5 and the walls of the recesses 14, and the parts will be securely held in their assembled relation, the weight of the fuel imposed upon the surface of the grate serving to even more firmly bind the parts. It will be evident that inasmuch as the interlocking parts are integral with the frame members 3 and 4, they will expand and contract to the same extent as the bodies of the said frame members. Therefore, there will be no likelihood of distortion of these parts or a fracture due to such expansion and contraction. Furthermore, by the construction illustrated and described the members of the frame may be conveniently assembled and disassembled without the manipulation of extraneous fastening means, and the installation of the frame and repairs thereto more readily effected than where bolts are employed in connecting the members of the frame.

The end members 4 of the frame structure may be provided with the usual supporting legs indicated by the numeral 20, as illustrated in Figures 1 and 2 of the draw-

ings, or if desired these legs may be provided upon the side members 3, and the ends of the end members 4 may be formed as in the instance of the ends of the side members 3, as shown in the drawings, and vice versa.

Having thus described the invention, what is claimed as new is:

1. In a grate structure, a frame comprising members to be connected together at the corners of the frame, one of said members having a recess and a boss upstanding therein and of wedge-shape, the other member having a recess providing a depending boss, the said recess and last-mentioned boss being formed to have wedging fit with the recess and boss of the first-mentioned member.

2. In a grate structure, a frame comprising members to be connected together at the corners of the frame, one of said members having a recess in its end and provided with an integral boss upstanding from the bottom wall of the recess and bounding the recess at one side, the said boss being wedge-shape in both horizontal and vertical section with its tapers extending in the direction of its upper end and in the direction of its side which forms juncture with the said member, the other member being formed with a depending boss defining a recess the walls of which are converged toward one side of the member and toward the upper end of the recess, whereby the boss of each member may have wedging engagement in the recess of the other member and thereby connect the members.

3. In a grate structure, a frame comprising members connected together at the corners of the frame, one of said members being provided with a recess in its end and with a boss upstanding from the bottom wall of the recess and provided with a laterally projecting rib, the boss and the rib being of wedge formation, the other member being formed with a recess opening through its under side and through its opposite side faces and providing a depending boss receivable within the recess in the first-mentioned member, the recess in the second-mentioned member being formed to accommodate the boss and rib of the first-mentioned member with a wedging fit.

In testimony whereof I affix my signature.

JAMES S. WILSON. [L.S.]
